UNITED STATES PATENT OFFICE.

JAMES C. BROWN, OF NEWARK, NEW JERSEY, ASSIGNOR TO E. FREDERICHS, INC., OF NEW YORK, N. Y., A CORPORATION OF NEW YORK.

HAIR-TREATING METHOD AND COMPOSITION.

No Drawing.

Application filed August 26, 1926. Serial No. 131,813.

- This invention relates to methods and compositions for the treatment of hair and particularly for imparting a "permanent wave" thereto.
- 5 An object of the invention is to provide an improved method of softening hair without deleteriously affecting the same.
- More specifically, the invention has for its object the provision of a method whereby
- 10 a tress of hair may be subjected to the softening action of ammonia gas through the duration of the permanent wave treatment.
- A further object is directed to the provision of a composition for use in a method
- 15 such as outlined above.

The invention accordingly comprises a method and a composition, both as exemplified in the following detailed disclosure, and the scope of the application of which will

20 be indicated in the claims.

The invention is primarily directed to the softening of human hair in order to permit the normal contour of the strands thereof to be altered in such manner, for example, 25 as will produce the effect commonly known as a "permanent wave", and accordingly the same will be exemplified in connection with a permanent waving treatment. In such treatments, a plurality of strands of hair

30 are commonly wound about a curler consisting ordinarily of a rod of any convenient type or size, and arranged to have heat applied thereto. About the coil of hair on the curler there is preferably wrapped a strip

35 of absorbent material or a pervious envelope, having a relatively impervious backing strip secured thereto in such manner that the latter will form a protective casing therefor when the same is wrapped about a

40 coil of hair. There may be employed, for example, an envelope of absorbent material and a backing strip, such as exemplified in the patent to Ernest O. Frederics, No. 1,596,247, dated August 17, 1926, and in the

45 copending application of said Ernest O. Frederics, Serial No. 97,365, filed March 26, 1926.

The present invention contemplates subjecting the hair to the softening influence 50 of ammonia gas in such quantities as will not be harmful to the hair, and preferably for such a duration as will cause a continuous softening of the hair through the permanent waving treatment. To this end, a

55 suitable pervious carrier may be employed

in the form of a casing in the manner exemplified in the patent to Ernest O. Frederics enumerated above, and an ammonia-releasing material enclosed therein, or preferably a carrier formed of absorbent material may be impregnated with a water admixture containing such material, and heat applied thereto while in proximity with the hair to be treated.

In the preferred manner of practicing the invention, a suitable carrier formed of absorbent material may be immersed in a bath containing a water admixture of a suitable material, such, for example, as an unstable ammonium salt, the carrier wrapped about a coil of hair upon a curler, and heat applied to this for a suitable period of time, for example from seven to ten minutes. In connection with the foregoing it is to be understood that by an unstable ammonium salt is meant any ammonium salt which will give off ammonia under the conditions of heat usually prevailing in the waving of hair. Ordinarily sufficient heat is applied to maintain the temperature of the materials about the hair at 100° C. The heat will cause a steady and continuous evolution of ammonia from the ammonia-releasing material throughout the duration of the treatment, and will consequently cause a continuous softening of the hair, which when dried will tend to hold the convolutions or undulations imparted thereto.

A satisfactory material for use has been found to be a borate of ammonia, preferably ammonium acid tetraborate, $\text{NH}_4\text{HB}_4\text{O}_7$, and when a water admixture of this material is employed, it preferably consists of a solution containing substantially 30 grams of ammonium acid tetraborate to each 250 c. c. of water. In cases where an accelerated evolution of ammonia is desirable, a certain amount of aqua-ammonia may be added to the admixture, in which case the amount of the borate employed may, if desired, be increased. For example, satisfactory results have been obtained by the use of an admixture containing substantially 15 grams of ammonium acid tetraborate and 25 c. c. of aqua-ammonia, 26° Bé., to each 250 c. c. of water.

While ammonium acid tetraborate has been exemplified as the preferred ammonium salt for use in accordance with the invention, it will be appreciated that other borates of

ammonia, such, for example, as ammonium mono-borate, $(\text{NH}_4)_3\text{BO}_3$, or ammonium tetraborate, $(\text{NH}_4)_2\text{B}_4\text{O}_7$ may also be employed.

5 Since certain changes in carrying out the above process and in the composition which embody the invention may be made without departing from the scope thereof, it is intended that all matter contained in the above 10 description shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I 20 claim as new and desire to secure by Letters Patent is:

1. A method of treating hair, which includes subjecting the hair to a substantially steady, continuous flow of ammonia for a 25 period of time.

2. A method of treating hair, which includes bringing into proximity with the hair to be treated a material chemically reactive to gradually release ammonia at an elevated 30 temperature, and applying heat to said material.

3. A method of treating hair, which includes bringing into proximity with the hair to be treated an unstable ammonium salt.

35 4. A method of treating hair, which includes bringing into proximity with the hair to be treated a borate of ammonia and water.

5. A method of imparting a permanent 40 wave to hair, which includes bringing into proximity with the hair to be treated a material containing a borate of ammonia, and applying heat thereto.

6. A method of treating hair, which includes bringing a borate of ammonia and 45 water into proximity with the hair to be treated, and heating the same to a temperature approximately 100° C.

7. A method of treating hair, which in-

cludes impregnating an absorbent carrier with an aqueous liquid containing a borate 50 of ammonia, wrapping said carrier about a coil of hair, and applying heat to said material.

8. A method of treating hair, which includes bringing an aqueous admixture of 55 ammonium acid tetraborate into proximity with the hair to be treated.

9. A method of treating hair, which includes impregnating an absorbent carrier with a solution containing substantially 60 30 parts by weight of ammonium acid tetraborate and substantially 250 parts by weight 65 of water, and applying heat to said carrier while in proximity with the hair to be treated.

10. A method of treating hair, which includes bringing into proximity with the hair to be treated an aqueous solution containing a borate of ammonia and ammonium hydroxide.

11. A method of treating hair, which includes impregnating an absorbent carrier with an aqueous solution containing substantial proportions of ammonium acid tetraborate and ammonium hydroxide.

12. A hair-treating composition comprising a borate of ammonia, and water.

13. A hair-treating composition comprising ammonium acid tetraborate and water.

14. A hair-treating composition comprising substantially 30 parts by weight of ammonium acid tetraborate, and substantially 250 parts by weight of water.

15. A composition for treating hair, including a borate of ammonia, ammonium hydroxide, and water.

16. A hair-treating composition comprising substantially 15 grams of ammonium acid tetraborate, and an amount of aqueous ammonia the effective ammoniacal strength 90 of which is substantially equivalent to that of 25 c. c. of aqua ammonia, 26° Bé., to each 250 c. c. of water.

In testimony whereof I affix my signature.

JAMES C. BROWN.
